UNITED STATES PATENT OFFICE.

OSCAR P. BENJAMIN, OF DETROIT, MICHIGAN, ASSIGNOR TO CAPITOL BRASS WORKS,
OF DETROIT, MICHIGAN, A CORPORATION OF MICHIGAN.

DESIGN FOR A COMBINED SINK BIBB.

Application filed March 20, 1922. Serial No. 1,252. Term of patent 14 years.

To all whom it may concern:

Be it known that I, OSCAR P. BENJAMIN, a citizen of the United States, residing at Detroit, in the county of Wayne and State of Michigan, have invented a new, original, and ornamental Design for a Combined Sink Bibb, of which the following is a specification, reference being had to the accompanying drawing, forming part thereof.

The figure is a perspective view of the combined sink bibb.

I claim.

The ornamental design for a combined sink bibb, as shown.

OSCAR P. BENJAMIN.
